MUSIC BOX WITH SELECTIVE OPERATION MEANS

David A. Goldman, Brooklyn, N. Y.

Application September 29, 1950, Serial No. 187,393

20 Claims. (Cl. 84—94)

1

The present invention relates in general to a music box and in particular to a record for playing a plurality of different musical selections on a music box.

The primary object of the present invention is the provision of a music box record which is utilized mechanically in determining the positions of a series of actuator elements to produce a desired musical selection on the music box.

Another object is the provision of a record by which the notes for a particular musical selection may be selected by one unfamiliar with musical notation and especially by a child unable to read letters or numbers.

A further object is the provision of a perforated record which may be mounted directly on a perforated carrier member in the music box, each side of the record having provision for selecting a plurality of different musical selections to be played by the music box.

The above and other objects, features and advantages of the present invention will be more fully understood from the following description considered in connection with the accompanying illustrative drawings.

In the drawings:

Fig. 1 is a front view of a music box provided with a record pursuant to the present invention, parts being broken away for illustration;

Fig. 2 is a sectional view, on a larger scale, taken on the line 2—2 of Fig. 1;

Fig. 3 is a sectional view, on a larger scale, taken on the line 3—3 of Fig. 1;

Fig. 4 is a fragmentary view of the record illustrated in Fig. 1;

Fig. 5 is a side view of another form of music box provided with a record pursuant to the present invention, portions being broken away for illustration;

Fig. 6 is a sectional view taken on the line 6—6 of Fig. 5; and

Fig. 7 is a front view of the record illustrated in Fig. 5.

Referring now to Figs. 1 through 4 in detail, there is shown the music box 10 which is provided with a record 12 pursuant to the present invention. As here shown, the music box 10 is provided with the opposing side walls 14 and 16, the opposing end walls 18 and 20, a bottom wall 22, and a top wall 24 provided with a central circular opening 26. A post 28 is mounted centrally of the bottom wall 22 by screws 30, said post supporting a member or disk 32 positioned in said opening 26 and mounted for rotation on said post. Said disk is provided with an open-

2

ing 34 at the center thereof, a screw 36 being threaded into post 28 through said opening. It will be noted that the screw has a loose fit in opening 34 and that the screw head 38 overlies said opening and is spaced from the disk.

To provide for the rotation of the disk 32, the latter is provided, adjacent the periphery thereof, with the circumferentially extending apertures 40 which cooperate with a drive mechanism 42. As here shown, the drive mechanism is of the manual type and comprises a crank shaft 44 which is mounted for rotation in an opening 46 which extends through the end wall 20. A toothed drive wheel 48 is mounted on the end 50 of shaft 44, interiorly of the box 10, by means of the screw 52. The teeth 54 on the periphery of the drive wheel 48 cooperate with the openings 40 in disk 32 for rotating the latter in a manner well known to those skilled in the art. The crank shaft 44 is provided with a handle portion 56, said portion being mounted in a flanged bushing 58 which is secured to the outer surface of the wall 20 by screws 60, a set screw 62 adjustably mounting the shaft in the bushing.

It will be noted that the disk 32 is disposed in the opening 26 in the upper wall 24 and, in order to retain said disk against movement outwardly of the box 10, provision is made for a cover 64 which is secured to the box by the screws 66, said cover being mounted directly upon the upper wall 24 and being provided with a central opening 68 having a smaller diameter than the opening 26 whereby the cover overlies a peripheral portion of the disk 32.

A music member or tone producing mechanism 70 is mounted on the bottom wall 22 between post 23 and the side wall 18. As here shown, the mechanism 70 is constituted by a comb of vibrating music tongues, tone elements, or reeds 72, which are of such size and shape, and are so arranged, that when they are caused to vibrate in order, they produce a musical scale. The reeds 72 may be of any desired number to produce any desired number of notes. As here shown, thirteen reeds 72 are provided, said reeds being mounted on a base 74 which is secured to the bottom wall 22 by means of the screws 76. It will be understood that the reeds 72 will be so chosen that they will correspond in tone with the notes of the musical scale and there will preferably be at least eight so that a complete octave can be played and said reeds should preferably be sufficient in number to contain all the sharps and flats within the octave.

As here shown, the disk 32 is provided with a plurality of concentric perforated circles 78, there being one circle for each of the reeds 72 and each circle being in registry with or in opposition to a companion reed. A hole 80 is provided in the disk 32 at each point of intersection between the circles 78 and radii of the disk to produce a series of radial rows 82 of said openings 80. Each of the perforated circles 78 is intended to cooperate with a specific reed 72 to produce one tone of the music box, the radial rows 82 determining the measure of the particular musical selection, the measure being varied by the speed of rotation of the disk 32.

In order to produce a particular musical note, an actuator or peg 84 is inserted in one of the concentric circles 78 for striking the free end of the companion reed of the particular circle, as the peg is rotated by disk 32 past the mechanism 70. It will be noted that the peg 84 is provided with a finger portion 86 and with a shank 88 of reduced diameter which extends through the opening 80 far enough into the box 10 to actuate a reed 72 as it is rotated past said reed. It will be apparent that any reed 72 may be actuated for producing a particular note by inserting the peg 84 in an opening 80 in the companion circle 78.

In order to play a particular musical selection on the music box 10, there is provided the aforementioned record 12. Said record is preferably formed of cardboard or any other suitable sheet material. The record 12, as here shown, is in the form of a disk similar to disk 32 but of lesser diameter. The record 12 is provided with the central aperture 90 through which the screw head 38 extends when the record is mounted on disk 32. Said record lies within the central opening 68 in the cover 64, the peripheral edge 69 of the record being spaced from the inner peripheral edge 71 of said cover. The record 12 is provided with a plurality of concentric circles 92 similar to the concentric circles 78 in the disk 32. Each of the circles 92 is apertured at 94 at each point of intersection between said circles and the record radii, in the same manner as the apertures 80 in disk 32. Therefore, it will be apparent that said apertured circles 92 also provide in the record the radial perforated rows 96 which are similar to the radial rows 82 in the disk. When the record 12 is mounted in position upon the disk 32, it will be understood that each of the concentric circles 92 of the record is in registry with each of the concentric circles 78 of the disk, and each of the radial rows 96 of the record is in registry with each of the radial rows 82 of the disk. With the record 12 so mounted on the disk 32, the actuators 84 will extend through the aligned apertures 94 and 80 of the record and the disk, respectively, for operating the reeds 72, as illustrated in Fig. 2.

For performing a particular musical selection, certain of the apertures 94 in the record 12 may be identified, in any suitable manner, to indicate the particular openings in the disk into which the pegs are to be inserted for playing said selection. For example, as shown in Fig. 4, certain of the apertures 94 have been encircled by a colored mark, as indicated at 98. Assuming now that the mark 98 represents a red circle, it will be understood that all of the notes comprising the particular selection are identified by red marks 98. Therefore, in order to play this particular selection, it is necessary only to insert the pegs 84 through the holes which are en-

circled in red on the record 12. If desired, any suitable indicia, for example, the arrow-head 99 may be provided on record 12 to indicate the start of the selection. When the handle 56 is operated to rotate the disk 32, the pegs 84 will actuate the reeds 72 in proper order to perform the selected musical selection.

To provide for the playing of additional selections with the same record 12, additional markings in other colors may be provided. For example, as illustrated in Fig. 4, green markings are provided at 100 and blue markings are provided at 102 indicating two additional selections which may be performed on the record 12. Therefore, it will be apparent that in order to perform any one of the three different selections indicated by the three different series of colored markings in Fig. 4, the operator need only be able to distinguish among the three different colors represented thereof. It will be understood that a greater or smaller number of different selections may be provided for on the particular record than as here shown, and that indicia other than colored circles may be used for this purpose. In addition, it will be understood that both sides of the record 12 may be provided with indicia so that each record may be used for a greater number of different selections. It will be apparent that the record may be removed from the disk 32 by first removing the pegs 84 and that the record may then be turned so that the other side abuts the disk 32, or the record may be replaced with a different record, it being noted that the pegs 84 serve to retain the record in position in the music box.

In the embodiment illustrated in Fig. 5, the invention is applied to a music box 104 which is provided with a drum or closed cylinder 106. As here shown, the music box 104 comprises a mounting member or support 108 having the opposing end walls 110 and 112, and the opposing side walls 114 and 116 integral with a bottom wall 118, said side walls being lower than said end walls. A music producing mechanism 120, which is similar in all respects to the music-producing mechanism 70, is mounted on the bottom wall 118, so that the reeds 122 are disposed in a plane perpendicular to the end walls 110 and 112. The drum or cylinder 106 is mounted for rotation between said end walls, said cylinder being provided with centrally disposed lateral extensions 123 and 124 at opposite sides, respectively, thereof. An axle 126 is secured in a recessed portion or seat 127 of extension 123 by the screw 128 and extends through a bearing aperture 130 formed in end wall at 110. A crank shaft 132 is similarly secured in a recessed portion or seat 133 of extension 124 by screw 134, said shaft extending through the bearing aperture 136 in the end wall 112. It will be understood that the bearing apertures 130 and 136 are in alignment. Crank shaft 132 is provided with a handle portion 138 for rotating the drum 106.

The drum 106 is provided with a plurality of circumferential perforated rings 140. The rings 140 are equal in number to the reeds 122, there being one ring of openings in registry with or in opposition to each of the reeds 122 so that each ring of openings is used to provide one particular note or tone. The openings 142 in the rings 140 are arranged in rows 144 which extend axially of the cylinder along the periphery thereof. Each of said rows 144 determines the measures of the particular piece of music in the same manner as the radial rows 82 in the disk 32. It will be ap-

parent that the pegs 84 may be placed in any opening in each of the rings 140 for producing a particular note upon actuating the particular reed 122 companion to said ring of openings.

The record 146 is used in conjunction with the music box 104 for setting up the pegs 84 to perform a particular musical selection in the same manner as the record 12. Record 146 is substantially rectangular in form and is provided with the longitudinal perforated rows 148 having the openings 150 which are arranged in transverse rows 152. When record 146 is mounted on cylinder 106, as in Fig. 5, rows 148 register with rows 140 in the cylinder and rows 152 register with rows 144 so that all openings 150 register with openings 142. It will be noted that the record 146 is provided with the colored rings 98, 100 and 102 as on the record 12. It will also be noted that the pegs 84 secure the record 146 in position on the drum 106, as illustrated in Figs. 5 and 6. As here illustrated, additional means are provided for securing the opposite ends 153 and 154 of record 46. As here shown, the record 146 is provided at end 154 with holes 156 and 158 which are spaced laterally outwardly of the longitudinal lines of openings 148 which correspond to the perforated circles 140 on the drum 106, it being understood that the transverse rows 152 of the record 146 correspond to the axial rows 144 on the drum 106. At its end 153 the record 146 is provided with the tabs 160 and 162 which are provided with the openings 164 and 166, respectively, which are in alignment with said openings 156 and 158, respectively. When the record 146 is mounted on the drum 106, the openings 164 and 166 will be in registry with the openings 156 and 158, respectively, and the pegs 168 may be inserted through said registered openings, as illustrated in Fig. 6, for retaining the ends of the record 146 against movement. It will be noted that since the pegs 168 are disposed laterally outwardly of the adjacent perforated circles 140 and 148, said pegs will not operate any of the reeds 122.

It will be understood that record 146 may also be marked on the opposite side thereof and that the number of selections indicated on each side may be more or less than as here shown and that other types of markings may be used.

It will be noted that the records, such as 12 and 146 or other records embodying the present invention, may be formed of paper since they need not be self-supporting and do not support the pegs 84.

While I have shown and described the preferred embodiments of my invention, it will be understood that various changes may be made in the present invention without departing from the underlying idea or principles of the invention within the scope of the appended claims.

Having thus described my invention, what I claim and desire to secure by Letters Patent, is:

1. A record for use with a music box having a music-producing member and an additional member, said members being movably mounted with respect to each other, said music-producing member having a series of elements tuned to a predetermined tone relationship, said additional member having defined therein series of apertures opposite said elements, respectively, to receive and hold a series of actuators in position at different points along lines extending in the direction of the relative movement of the members for causing said elements to sound when the members are given a relative movement, said actuators being removably mounted in said aper-

tures and shiftable to different positions along said lines for causing said elements to sound in the desired predetermined order and timed relation; said record being removably mountable on said additional member and being provided with a series of apertures similar to said series in said additional member so that the apertures in said record are in registry with the apertures in said additional member when said record is mounted thereon, whereby said actuators are receivable in registered pairs of said apertures, and indicia means at selected record apertures for indicating selected points along said lines at which actuators are to be positioned for playing a predetermined musical selection.

2. A record for use with a music box having a music-producing member and an additional member, said members being movably mounted with respect to each other, said music-producing member having a series of elements tuned to a predetermined tone relationship, said additional member having defined therein series of apertures opposite said elements, respectively, to receive and hold a series of actuators in position at different points along lines extending in the direction of the relative movement of the members for causing said elements to sound when the members are given a relative movement, said actuators being removably mounted in said apertures and shiftable to different positions along said lines for causing said elements to sound in the desired predetermined order and timed relation; said record being removably mountable on said additional member and being provided with a series of apertures opposite said elements, respectively, to receive and hold a series of actuators in position at different points along lines extending in the direction of the relative movement of the members for causing said elements to sound when the members are given a relative movement, said actuators being removably mounted in said apertures and shiftable to different positions along said lines for causing said elements to sound in the desired predetermined order and timed relation; said record being removably mountable on said additional member and being provided with a series of apertures similar to said series in said additional member so that the apertures in said record are in registry with the apertures in said additional member when said record is mounted thereon, whereby said actuators are receivable in registered pairs of said apertures, and a plurality of indicia series, each at selected record apertures, respectively, each of said indicia series indicating a series of selected points along said lines at which actuators are to be positioned for playing a predetermined musical selection.

3. A record for use with a music box having a music-producing member and an additional member, said members being movably mounted with respect to each other, said music-producing member having a series of elements tuned to a predetermined tone relationship, said additional member having defined therein series of apertures opposite said elements, respectively, to receive and hold a series of actuators in position at different points along lines extending in the direction of the relative movement of the members for causing said elements to sound when the members are given a relative movement, said actuators being removably mounted in said apertures and shiftable to different positions along said lines for causing said elements to sound in the desired predetermined order and timed relation; said record being removably mountable on said additional member and being provided with a series of apertures similar to said series in said additional member so that the apertures in said record are in registry with the apertures in said additional member when said record is mounted thereon, whereby said actuators are receivable in registered pairs of said apertures, and indicia means on the opposite surfaces of said record, the indicia means at each surface indicating selected record apertures for indicating selected

points along said lines at which actuators are to be positioned for playing a predetermined musical selection.

4. A record for use with a music box having a music-producing member and an additional member, said members being movably mounted with respect to each other, said music-producing member having a series of elements tuned to a predetermined tone relationship, said additional member having defined therein series of apertures opposite said elements, respectively, to receive and hold a series of actuators in position at different points along lines extending in the direction of the relative movement of the members for causing said elements to sound when the members are given a relative movement, said actuators being removably mounted in said apertures and shiftable to different positions along said lines for causing said elements to sound in the desired predetermined order and timed relation; said record being removably mountable on said additional member and being provided with a series of apertures similar to said series in said additional member so that the apertures in said record are in registry with the apertures in said additional member when said record is mounted thereon, whereby said actuators are receivable in registered pairs of said apertures, and indicia means at selected record apertures for indicating selected points along said lines at which actuators are to be positioned for playing a predetermined musical selection, said record having a form similar to the form of said additional member for movement thereby.

5. A record for use with a music box having a music-producing member and an additional member, said members being movably mounted with respect to each other, said music-producing member having a series of elements tuned to a predetermined tone relationship, said additional member having defined therein series of apertures opposite said elements, respectively, to receive and hold a series of actuators in position at different points along lines extending in the direction of the relative movement of the members for causing said elements to sound when the members are given a relative movement, said actuators being removably mounted in said apertures and shiftable to different positions along said lines for causing said elements to sound in the desired predetermined order and timed relation; said record being removably mountable on said additional member and being provided with a series of apertures similar to said series in said additional member so that the apertures in said record are in registry with the apertures in said additional member when said record is mounted thereon, whereby said actuators are receivable in registered pairs of said apertures, said record being retained in fixed position on said member by said actuators.

6. A record for use with a music box having a music-producing member and an additional member, said members being movably mounted with respect to each other, said music-producing member having a series of elements tuned to a predetermined tone relationship, said additional member having defined therein series of apertures opposite said elements, respectively, to receive and hold a series of actuators in position at different points along lines extending in the direction of the relative movement of the members for causing said elements to sound when the members are given a relative movement, said actuators being removably mounted

in said apertures and shiftable to different positions along said lines for causing said elements to sound in the desired predetermined order and timed relation; said record being removably mountable on said additional member and being provided with a series of apertures similar to said series in said additional member so that the apertures in said record are in registry with the apertures in said additional member when said record is mounted thereon, whereby said actuators are receivable in registered pairs of said apertures, and indicia means at selected record apertures for indicating selected points along said lines at which actuators are to be positioned for playing a predetermined musical selection, said indicia means being colored markings at the selected record apertures.

7. In a music box having a music-producing member and an additional member, said members being movably mounted with respect to each other, said music-producing member having a series of music-producing elements tuned to a predetermined tone relationship, said additional member having defined therein series of apertures opposite said elements, respectively, to receive and hold a series of actuators in position at different points along lines extending in the direction of the relative movement of the members for causing said elements to sound when the members are given a relative movement, said actuators being removably mounted in said apertures and shiftable to different positions along said lines for causing said elements to sound in the desired predetermined order and timed relation; the combination with said actuators of a record adapted for removable mounting on said additional member, said record having a series of apertures similar to said series in said additional member so that the apertures in said record are in registry with the apertures in said additional member when said record is mounted thereon, said actuators being receivable in registered pairs of said apertures whereby said record is retained in fixed position on said additional member.

8. In a music box having a music-producing member and an additional member, said members being movably mounted with respect to each other, said music-producing member having a series of music-producing elements tuned to a predetermined tone relationship, said additional member having defined therein series of apertures opposite said elements, respectively, to receive and hold a series of actuators in position at different points along lines extending in the direction of the relative movement of the members for causing said elements to sound when the members are given a relative movement, said actuators being removably mounted in said apertures and shiftable to different positions along said lines for causing said elements to sound in the desired predetermined order and timed relation; the combination with said actuators of a record adapted for removable mounting on said additional member, said record having a series of apertures similar to said series in said additional member so that the apertures in said record are in registry with the apertures in said additional member when said record is mounted thereon, said actuators being receivable in registered pairs of said apertures whereby said record is retained in fixed position on said additional member, and indicia means at selected record apertures for indicating selected points along said lines at which actuators are to be

positioned for playing a predetermined musical selection.

9. A record for use with a music box provided with a series of musical elements each tuned to a related tone and a member mounted for movement relative to said elements, said member having a series of apertures for each of said elements, respectively, each of said series extending in the direction of movement of said member, and actuators removably mounted in said apertures and shiftable to different positions in each of said series of apertures for causing said elements to sound in the desired predetermined order and timed relation as said actuators are moved past said elements; said record being removably mountable on said member for movement thereby, said record being provided with similar aperture series each in registry with a companion aperture series, respectively, in said member when said record is mounted thereon, whereby said actuators are receivable in registered pairs of said apertures, and indicia means at selected record apertures for indicating selected points along said aperture series in said member at which actuators are to be positioned for playing a predetermined musical selection.

10. A record for use with a music box provided with a series of musical elements each tuned to a related tone and a member mounted for movement relative to said elements, said member having a series of apertures for each of said elements, respectively, each of said series extending in the direction of movement of said member, and actuators removably mounted in said apertures and shiftable to different positions in each of said series for causing said elements to sound in the desired predetermined order and timed relation as said actuators are moved past said elements; said record being removably mountable on said member for movement thereby, said record being provided with a similar aperture series each in registry with a companion aperture series, respectively, in said member when said record is mounted thereon, whereby said actuators are receivable in registered pairs of said apertures, said record being retained in position on said member by said actuators.

11. A record for use with a music box provided with a series of musical elements each tuned to a related tone and a member mounted for movement relative to said elements, said member having a series of apertures for each of said elements, respectively, each of said series extending in the direction of movement of said member, and actuators removably mounted in said apertures and shiftable to different positions in each of said series for causing said elements to sound in the desired predetermined order and timed relation as said actuators are moved past said elements; said record being removably mountable on said member for movement thereby, said record being provided with similar aperture series each in registry with a companion aperture series, respectively, in said member when said record is mounted thereon, whereby said actuators are receivable in registered pairs of said apertures, and a plurality of indicia series, each at selected record apertures, respectively, each of said indicia series indicating a series of selected points along said aperture series in said member at which actuators are to be positioned for playing a predetermined musical selection.

12. A record for use with a music box provided with a series of musical elements each tuned to

a related tone and a member mounted for movement relative to said elements, said member having a series of apertures for each of said elements, respectively, each of said series extending in the direction of movement of said member, the apertures in each of said series being aligned in additional series extending transversely of said first mentioned series for determining the measure of a musical selection, and actuators removably mounted in said apertures and shiftable to different positions in each of said first mentioned series for causing said elements to sound in the desired predetermined order and timed relation as said actuators are moved past said elements;

- 15 said record being removably mountable on said member for movement thereby, said record being provided with apertures arranged in both said first mentioned and said additional series, the aperture series of said record being in registry with companion aperture series, respectively, in said member when said record is mounted thereon, whereby said actuators are receivable in registered pairs of said apertures, and indicia means at selected record apertures for indicating selected points along said first mentioned aperture series in said member at which actuators are to be positioned for playing a predetermined musical selection.
- 20
- 25

- 13. A record for use with a music box provided with a series of musical elements each tuned to a related tone and a disk mounted for rotation relative to said elements, said disk having a series of apertured concentric circles, there being one circle for each of said elements, respectively, the apertures in said circles being aligned along radii of said disk, and actuators removably mounted in said apertures and shiftable to different positions in each of said concentric circles for causing said elements to sound in the desired predetermined order and timed relation as said disk is rotated; said record comprising a disk removably mountable on said first mentioned disk for rotation thereby, said record being provided with similar apertured concentric circles, the apertures in said record circles being aligned along radii of said record so that the apertures of said record are in registry with the apertures in said first mentioned disk when said record is mounted thereon, whereby said actuators are receivable in registered pairs of said apertures, and indicia means at selected record apertures for indicating selected points along said concentric circles in said first mentioned disk at which actuators are to be positioned for playing a predetermined musical selection.

said actuators being receivable in registered pairs of said apertures whereby said record is retained in fixed position on said first mentioned disk.

15. A record for use with a music box provided with a series of musical elements, each tuned to a related tone and a cylinder mounted for rotation relative to said elements, said cylinder having in its peripheral surface series of apertures extending circumferentially thereof, there being one series for each of said elements, respectively, the apertures in said series being arranged in additional series extending axially of said cylinder, and actuator removably mounted in said apertures and shiftable to different positions in each of said circumferential series for causing said elements to sound in the desired predetermined order and timed relation as said cylinder is rotated; said record comprising a member removably mountable on the peripheral surface of the cylinder, said record being provided with longitudinal aperture series, the apertures in each of said longitudinal series being aligned in additional series extending transversely of said record whereby, when said record is mounted on said cylinder, said longitudinal series are in registry with said circumferential series, respectively, and said transverse series are in alignment with said axially extending series, respectively, so that said actuators are receivable in registered pairs of said apertures, and indicia means at selected record apertures for indicating selected points along said circumferential series at which actuators are to be positioned for playing a predetermined musical selection.

16. A record for use with a music box provided with a series of musical elements each tuned to a related tone and a cylinder mounted for rotation relative to said elements, said cylinder having in its peripheral surface series of apertures extending circumferentially thereof, there being one series for each of said elements, respectively, the apertures in said series being arranged in additional series extending axially of said cylinder, and actuators removably mounted in said apertures and shiftable to different positions in each of said circumferential series for causing said elements to sound in the desired predetermined order and timed relation as said cylinder is rotated; said record comprising a member removably mountable on the peripheral surface of the cylinder, said record being provided with longitudinal aperture series, the apertures in each of said longitudinal series being aligned in additional series extending transversely of said record whereby, when said record is mounted on said cylinder, said longitudinal series are in registry with said circumferential series, respectively, and said transverse series are in alignment with said axially extending series, respectively, so that said actuators are receivable in registered pairs of said apertures, and indicia means at selected record apertures for indicating selected points along said circumferential series at which actuators are to be positioned for playing a predetermined musical selection, and means for retaining the ends of said record in fixed position on said cylinder.

17. In a music box provided with a series of musical elements each tuned to a related tone and a cylinder mounted for rotation relative to said elements, said cylinder having on its peripheral surface series of apertures extending circumferentially thereof, there being one series for each of said elements, respectively, the apertures in said series being arranged in additional series extending axially of said cylinder, and actuators

removably mounted in said apertures and shiftable to different positions in each of said circumferential series for causing said elements to sound in the desired predetermined order and timed relation as said cylinder is rotated; the combination with said actuators of a record removably mountable on the peripheral surface of said cylinder, said record being provided with longitudinal aperture series, the apertures in each of said longitudinal series being aligned in additional series extending transversely of said record whereby, when said record is mounted on said cylinder, said longitudinal series are in registry with said circumferential series, respectively, and said transverse series are in alignment with said axially extending series, respectively, so that said actuators are receivable in registered pairs of said apertures for retaining the record in fixed position on said cylinder.

20. 18. In a music box provided with a series of musical elements each tuned to a related tone and a cylinder mounted for rotation relative to said elements, said cylinder having on its peripheral surface series of apertures extending longitudinally thereof, there being one series for each of said elements, respectively, the apertures in said series being arranged in additional series extending axially of said cylinder, and actuators removably mounted in said apertures and shiftable to different positions in each of said circumferential series for causing said elements to sound in the desired predetermined order and timed relation as said cylinder is rotated; the combination with said actuators of a record removably mountable on the peripheral surface of said cylinder, said record being provided with longitudinal aperture series, the apertures in each of said longitudinal series being aligned in additional series extending transversely of said record whereby, when said record is mounted on said cylinder, said longitudinal series are in registry with said circumferential series, respectively, and said transverse series are in alignment with said axially extending series, respectively, so that said actuators are receivable in registered pairs of said apertures for retaining the record in fixed position on said cylinder.

25. 19. A record for use with a music box provided with a series of musical elements each tuned to a related tone and a cylinder mounted for rotation relative to said elements, said cylinder having in its peripheral surface series of apertures extending circumferentially thereof, there being one series for each of said elements, respectively, the apertures in said series being arranged in additional series extending axially of said cylinder, and actuators removably mounted in said apertures and shiftable to different positions in each of said circumferential series for causing said elements to sound in the desired predetermined order and timed relation as said cylinder is rotated; said record comprising a rectangular flexible member removably mountable on the peripheral surface of said cylinder, said record being provided with longitudinal aperture series, the apertures in each of said longitudinal series being aligned in additional series extending transversely of said record whereby, when said record is mounted on said cylinder, said longitudinal series are in registry with said circumferential series, respectively, and said transverse series are in alignment with said axially extending series, respectively, so that said actuators are

receivable in registered pairs of said apertures, and indicia means at selected record apertures for indicating selected points along said circumferential series at which actuators are to be positioned for playing a predetermined musical selection.

20. A record for use with a music box provided with a series of musical elements each tuned to a related tone and a cylinder mounted for rotation relative to said elements, said cylinder having in its peripheral surface series of apertures extending circumferentially thereof, there being one series for each of said elements, respectively, the apertures in said series being arranged in additional series extending axially of said cylinder, and actuators removably mounted in said apertures and shiftable to different positions in each of said circumferential series for causing said elements to sound in the desired predetermined order and timed relation as said cylinder is rotated; said record comprising a rectangular flexible member removably mountable on the peripheral surface of said cylinder, said record being provided with longitudinal aperture series, the apertures in each of said longitudinal series being aligned in additional series extending transversely of said record whereby, when said

5 record is mounted on said cylinder, said longitudinal series are in registry with said circumferential series, respectively, and said transverse series are in alignment with said axially extending series, respectively, so that said actuators are receivable in registered pairs of said apertures, and indicia means at selected record apertures for indicating selected points along said circumferential series at which actuators are to be positioned for playing a predetermined musical selection, and means at the opposite ends of said rectangular member for retaining said ends in position in said cylinder.

15 DAVID A. GOLDMAN.
